(57) **CLAIM**

The ornamental design for a mount for mounting accessories on a handlebar, as shown and described.

DESCRIPTION

FIG. 1 is a front perspective view of the mount in a closed position shown from the left hand side;

FIG. 2 is another front perspective view of the mount in the closed position shown from the right hand side;

FIG. 3 is a front elevation view of the mount in the closed position;

FIG. 4 is a rear elevation view of the mount in the closed position;

FIG. 5 is a left side elevation view of the mount in the closed position;

FIG. 6 is a right side elevation view of the mount in the closed position;

FIG. 7 is a top plan view of the mount in the closed position;

FIG. 8 is a bottom plan view of the mount in the closed position;

FIG. 9 is a front perspective view of the mount in an open position shown from the left hand side;

FIG. 10 is another front perspective view of the mount in the open position shown from the right hand side;

FIG. 11 is a front elevation view of the mount in the open position;

FIG. 12 is a rear elevation view of the mount in the open position;

FIG. 13 is a left side elevation view of the mount in the open position;

FIG. 14 is a right side elevation view of the mount in the open position;

FIG. 15 is a top plan view of the mount in the open position;

FIG. 16 is a bottom plan view of the mount in the open position; and,

FIG. 17 is a front perspective view of the mount in the open and twisted position shown from the left hand side.
